UNITED STATES PATENT OFFICE.

HENRI G. LEVY, OF SAN FRANCISCO, CALIFORNIA.

FLUID MIXER.

1,417,927.

Specification of Letters Patent. Patented May 30, 1922.

Application filed May 9, 1921. Serial No. 467,804.

To all whom it may concern:

Be it known that I, HENRI G. LEVY, a citizen of the United States, and a resident of the city and county of San Francisco, State of California, have made a new and useful invention—to wit, Improvements in Fluid Mixers; and I do hereby declare the following to be a full, clear, concise and exact description of the same.

10 This invention relates particularly to fluid mixers.

An object of this invention is to provide an electrically operated fluid mixer for use at drink mixing dispensers which will be 15 superior in point of simplicity and inexpensiveness of construction, positiveness of operation, facility and convenience in use and general efficiency as contrasted with any device of a similar nature. Other objects 20 and advantages will appear as this description progresses.

In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention 30 in whatsoever form it may be embodied.

In the accompanying two-sheets of drawings,

Figure 1 represents a front elevation of a drink mixing device mounted on a supporting pedestal.

Figure 2 represents a side elevation of Figure 1.

Figure 3 represents a modified side view of Figure 1.

40 Figure 4 represents a plan view through Figure 1 on the line 4—4.

In detail the construction illustrated in the drawings comprises a hollow standard 1 or other equivalent supporting medium, the 45 end thereof flaring into a base 2, adapted to rest upon either a counter or marble 3. Where the complete mixer maintains a semi-permanent position, it is desirable that the base 2 of the standard 1 be provided with 50 an extended lip 4 through which a clamping screw 5 or other equivalent means may be passed for frictionally engaging the counter or other element upon which the standard 1 is mounted. The opposite end 55 6 of the standard 1 terminates in a saddle-like fastening to which an electrically oper-

ated motor 7, or the equivalent thereof, is adapted to be securely fixed by means of machine screws 8 passing through the said end 6 into the motor housing. It is desirable 60 that the motor be positioned on the end 6 of the standard so that the commutator shaft is disposed substantially parallel with the axis of the standard 1. A suitable agitator or mixer shaft 9 is secured on the end of 65 the commutator shaft by means of the coupling 10 or other equivalent media.

A platform for supporting a fluid container, comprising a flat shelf portion 11 having a peripheral rim 12 therearound and 70 provided with spaced rearwardly extending projections or arms 13 and 14 thereon is pivoted by the shaft 15 to an integral projection 16 formed on the standard 1. This construction is clearly shown in Figure 4 75 where the spaced outwardly flaring arms 13 and 14 extend on opposite sides of the standard so as to permit the weighted ends of said projections passing on each side of the standard. The arms 13 and 14 increase in 80 cross section from the junction point to the heavily weighted ends, which serve as counter-balances tending to normally elevate the shelf portion 11. Integral lugs 17 and 18 are formed on opposite undersides of the 85 projection 16 and act as stops to prevent any downward movement of the weighted arms 13 and 14. Thus it is possible to depress the shelf portion of the platform about its pivot point 15 at the same time elevating the 90 counter-balances 13 and 14, so that upon releasing the downwardly moving force from the shelf portion, the weighted arms through gravity will move back into a normal position, substantially at right angles to either 95 of the axes of the agitator 9 or standard 1.

This invention operates as follows:

A fluid compound to be agitated or a beverage to be mixed would be placed in a suitable container or vessel 20 and which 100 would be grasped by one hand of the attendant. With the other hand, the attendant would depress the shelf of the platform 11 so that the throat of the container could be passed within the space 23 between the separated ends of the rim 12 and also within the space 24 between the separated rim ends at the point substantially diametrically opposite the front opening 23 aforementioned, 105 to permit the glass or container being passed around the agitator 9. After the container has been moved to the proper height rela-

tive to the agitator, the operator would permit the platform or shelf to be elevated so that the glass or container could rest thereon substantially as shown in Figures 1 and 2. 5 At the completion of this operation, one of the fingers of the operator would be extended to operate the control switch 25 through suitable current carrying conduits connecting a source of energy with the motor 6, 10 starting it in operation.

It will be noticed that the axis of the agitator shaft is positioned eccentrically to the axis of the pivot platform and container so that when the agitator shaft is started rotating, 15 it will completely swirl and intermix the ingredients. In standard practice where the agitator shaft is placed concentrically with the axis of the fluid container, the effect of the rotary motion and centrifugal action 20 is to throw all of the ingredients away from and out of contact with the agitator shaft, whereas the eccentric arrangement of the agitator shaft and drink container has proven a very efficient means for obtaining 25 a frothy and creamy mixture.

Having thus described my invention, what I claim and desire to secure by Letters Patent is:

1. A device such as described, comprising 30 in combination a standard; a motor fixed thereon and having an agitator projecting therefrom; and a platform pivotally mounted on said standard and having counterbalance arms extending on both sides of said 35 standard.

2. A device such as described, comprising 40 in combination a standard; a motor fixed thereon and having an agitator projecting therefrom; a platform pivotally mounted on said standard and having counterbalance arms extending on both sides of said standard; and means on said standard for engaging 45 said platform to hold it at substantially

right angles to the vertical axis of said standard. 45

3. A device such as described, comprising in combination a standard; a motor fixed thereon and having an agitator projecting therefrom; a platform pivotally mounted on the front side of said standard, adjacent said 50 agitator, having counterbalance arms thereon extending rearwardly on both sides of said standard, adapted to maintain said platform substantially at right angles to the axis of said agitator; and a rim around said platform having a gap through the front part thereof. 55

4. A device such as described comprising in combination a standard, a motor on said standard, having an agitator projecting 60 therefrom, a platform, pivotally mounted on said standard, and having counterbalance arms extending on both sides of said standard to maintain it at substantially right angles to the axis of said standard and means 65 on said platform for positioning a container eccentrically to the axis of said agitator.

5. A device such as described comprising in combination a standard; a motor on said standard having an agitator projecting 70 therefrom; a platform, pivotally mounted on said standard, and having counterbalance arms extending on both sides of said standard to maintain it at substantially right angles to the axis of said standard; means on 75 said platform for positioning a container eccentrically to the axis of said agitator and a motor control switch on said standard adjacent the pivoted platform.

In testimony whereof, I have hereunto set 80 my hand at San Francisco, California, this 30th day of April 1921.

HENRI G. LEVY.

In presence of—

LINCOLN V. JOHNSON.
